US00D934151S

(12) **United States Design Patent** (10) **Patent No.:** **US D934,151 S**
(45) **Date of Patent:** **** Oct. 26, 2021**

(54) **AERIAL VEHICLE**(71) Applicant: **SZ DJI Technology Co., Ltd.**,
Shenzhen (CN)(72) Inventors: **Bo Liang**, Shenzhen (CN); **Li Qiu**,
Shenzhen (CN)(73) Assignee: **SZ DJI Technology Co., Ltd.**,
Shenzhen (CN)(**) Term: **15 Years**(21) Appl. No.: **29/745,842**(22) Filed: **Aug. 10, 2020****Related U.S. Application Data**

(63) Continuation of application No. 29/701,938, filed on Aug. 15, 2019, now Pat. No. Des. 896,731, which is a continuation of application No. 29/642,455, filed on Mar. 29, 2018, now Pat. No. Des. 862,360, which is a continuation of application No. 29/595,105, filed on Feb. 24, 2017, now Pat. No. Des. 816,582.

(51) **LOC (13) Cl.** **12-02**(52) **U.S. Cl.**USPC ..... **D12/328**(58) **Field of Classification Search**USPC D12/1-4, 16.1, 319-345; D21/436-455;

Primary Examiner — Marissa J Cash(74) *Attorney, Agent, or Firm* — Sterne, Kessler,
Goldstein & Fox P.L.L.C.(57) **CLAIM**

The ornamental design for an aerial vehicle, as shown and described.

DESCRIPTION

FIG. 1 is a top front perspective view of an aerial vehicle showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the aerial vehicle that form no part of the claimed design.

1 Claim, 8 Drawing Sheets(56)
